UNITED STATES PATENT OFFICE.

CHARLES W. HALL, OF PRINCETON, WEST VIRGINIA.

RAILWAY GRADE-CROSSING GATE.

Application filed September 13, 1923. Serial No. 662,573.

To all whom it may concern:

Be it known that I, CHARLES W. HALL, a citizen of the United States, residing at Princeton, in the county of Mercer and State of West Virginia, have invented certain new and useful Improvements in Railway Grade-Crossing Gates, of which the following is a specification.

The present invention relates to grade crossing gates for railroads and electric railway lines, and the main object is to construct a gate so that it is closed and opened automatically by a passing train.

For this reason the gate is provided with a motor, the switch of which is normally closed and remains closed upon a train entering the block where the gate is positioned, said switch, however, opening automatically to disconnect the motor as soon as the gate has been lowered.

Another object of the invention is to hold the gate securely in lowered position until the train passes out of the block when the gate is immediately opened and the switch closed.

In the accompanying drawings, one embodiment of the invention is illustrated, and—

Figure 1 is a diagram of the circuit connected with the rails for automatically operating the gate;

Figure 2 is a side elevation of the gate in open position;

Figure 3 is a section along line 3—3 of Figure 2;

Figure 4 is a side elevation and partial section showing the gate closed;

Figure 5 is a section along line 5—5 of Figure 3, and—

Figure 6 is a side elevation of a switch for the motor.

In the drawings, the reference numeral 10 represents a stand forming bearings for a horizontal shaft 11 upon which a gate beam 12 is rigidly mounted. The gate beam has a counter-weight 13 tending to maintain the same in upright position. The shaft 11 extends through the stand and on the extending portion is secured a brake drum 14. On the stand 10 is secured, as at 15, one end of a brake band 16 surrounding the drum but standing normally free therefrom. The other end of the brake band carries a projecting arm 17 which is preferably made of soft iron to form an armature for

an electro-magnet 18 which is rigidly mounted on the stand 10 in the path of the arm 17.

Outside of the drum 14 is keyed on the shaft 11 a lever 19. This lever extends in both directions diametrically across the drum and the end shown uppermost in Figs. 2 and 3 carries a finger 20 extending transversely in the direction of the stand 10 so as to engage with the arm 17 when the gate beam 12 is lowered. The other end of the lever 19 is provided with an abutment 21 also projecting inwardly from the lever and intended to contact with the end of a switch 22 to throw the same out when the gate beam 12 is nearing its lowered position. The switch 22 is normally closed by a spring 23, or in any other suitable manner (see Figure 6). At 24 is shown a frame bolted to the stand 10, as at 25, and preferably engaging, as at 26, the outer end of the shaft 11. Upon this frame is mounted an electric motor 27. The motor shaft carries a pinion 28 between which and a gear wheel 29 revolvably mounted on the free end of the shaft 11, is inserted a train of gears 30 in order to reduce the motor speed sufficiently for lowering the gate beam 12 slowly. The gear wheel 29 carries a spring dog 44 engaging with a ratchet wheel 45 keyed at the free end of the shaft 11. In this manner the shaft 11 may be turned by the gear wheel 29 when the motor is running while the shaft 10 is free to rotate while the motor is standing. It is evident that instead of the train of gears for operating the shaft 11, a silent chain drive or similar transmission may be used.

At 31 is shown a pair of signaling lamps for indicating the closed position of the gate.

Referring more particularly to Figure 1 of the drawings, reference numerals 32 and 33 represent a pair of rails in the block of a track where the gate is positioned. These rails are insulated, as at 34. The rail 33 is shown connected, as at 35, by a live wire 36 with a source of electric power. The other rail 32 is connected with the switch 22 by means of a conductor 37 and another conductor 38 connects the switch with the motor 27. The motor is grounded, as at 39, by means of a conductor 40. This constitutes the main circuit. A shunt connection for the electro-magnet 18 is indicated by conductor 110

tors 41 and 42 connected to the above described main circuit.

The operation of the gate is as follows:

The gate beam 12 actuated by the counter-weight 13 is normally in raised position as indicated in Figures 2, 3 and 5 when the switch 22 is closed and the brake 16 free. As soon as a train enters the insulated block of the track, the wheels and axle 43 of the train close the gap between the rails forming the main circuit so that current runs from the wire 36, rail 33, axle 43, rail 32, conductor 37, through the switch 22 and from there over the conductor 38 to the motor 27 and back to ground over the conductor 40. The motor 27 is then immediately started and through the intermediary of the gears 28, 30, 29 and 45 the shaft 11 is turned, thus swinging the gate beam 12 into lowered position. The brake drum 14 and the lever 19 are simultaneously rotated and when the gate is nearing its lowered position the finger 20 will contact with the arm 17, thereby gradually tightening the brake band 16 around the drum 14 so that by the time the gate beam has been fully lowered, the brake will be applied. Simultaneously, the arm 17 which constitutes an armature will be attracted by the electro-magnet 18, as the shunt circuit 41, 42 will also be closed, and magnetize the electro-magnet 18. The brake band will thus be held tightly around the drum 14 when the armature 17 is drawn down by the electro-magnet 18.

As the end of the lever 19 carrying the abutment 21 has simultaneously traveled in upward direction, it reaches the switch 22 nearly at the same time as the armature 17 is attracted by the electro-magnet 18 thus opening the switch and breaking the main circuit to the motor 27 which will then immediately stop. As, however, the shunt circuit remains closed by the wheels and axle 43 of the train, the electro-magnet 18 retains its hold upon the armature 17 and keeps the brake in operation.

As soon as the train has left the block and the wheels and axle 43 of the last car pass beyond the insulations 34, the gap between the rails 32 and 33 is again opened so that no current will pass to the electro-magnet 18. The latter is accordingly immediately demagnetized and releases the armature 17 when the brake band 16 springs into open position and the counter-weight 13 thereupon brings the gate beam into raised position as indicated in Figures 2, 3 and 5, the shaft 11 then revolving freely with respect to the gear wheel 29.

It is evident that instead of the brake drum having an external band as shown in the drawings, an internally operated brake drum may be used.

The lamps 31 are in the same circuit as the magnet 18 so that as long as the magnet is

active the lamps will be lighted. In other words, a stop signal is given whenever the gate remains in closed or lowered position.

Having thus described the invention, what is claimed as new is:

1. In a railway gate, the combination with an insulated block of rails; of a weighted gate beam standing normally in upright position, a motor adapted to lower said gate beam, a main circuit including a switch for said motor and connected with a source of power, said rails providing a gap in said circuit, an element connected with said beam for opening said main switch when the beam is in lowered position, and a brake actuated by said element to hold the beam in lowered position.

2. In a railway gate, the combination with an insulated block of rails; of a weighted gate beam standing normally in upright position, a motor adapted to lower said gate beam, a main circuit including a switch for said motor and connected with a source of power, said rails providing a gap in said circuit, an element connected with said beam for opening said main switch when the beam is in lowered position, means retaining the beam in said lowered position, and a brake actuated by said element when said beam is in lowered position.

3. In a railway gate, the combination with an insulated block of rails; of a weighted gate beam standing normally in upright position, a motor adapted to lower said gate beam, a main circuit including a switch for said motor and connected with a source of power, said rails providing a gap in said circuit, an element connected with said beam for opening said main switch when the beam is in lowered position, means retaining the beam in said lowered position, said means including a shunt circuit actuated by said main circuit, an electro-magnet in the shunt circuit, an armature mounted on said gate beam, and a brake actuated by said element when said beam is in lowered position.

4. In a railway gate, the combination with an insulated block of rails; of a weighted gate beam standing normally in upright position, a motor adapted to lower said gate beam, a main circuit including a switch for said motor and connected with a source of power, said rails providing a gap in said circuit; a shaft upon which said beam is secured, an arm fixedly mounted on the shaft, an abutment on the arm adapted to engage said switch a moment before the lowered position thereby opening said switch, and a brake inserted between said arm and said shaft.

5. In a railway gate, the combination with an insulated block of rails; of a weighted gate beam standing normally in upright position, a motor adapted to lower said gate beam, a main circuit including a switch for

said motor and connected with a source of power, said rails providing a gap in said circuit; a shaft upon which said beam is secured, an arm fixedly mounted on the shaft, 5 an abutment on the arm adapted to engage said switch to open the same a moment before the lowered position of said beam has been reached, a brake inserted between said arm and said shaft, said brake including a 10 drum united with said shaft, and a brake band for said drum actuated by said arm.

6. In a railway gate, the combination with an insulated block of rails; of a weighted gate beam standing normally in upright position, a motor, a main circuit including a 15 switch for said motor connected with a source of power, said rails providing a gap in said circuit; a shaft upon which said beam is secured, a train of gears between 20 said motor and said shaft, an arm fixedly mounted on the shaft, an abutment on the arm adapted to engage said switch to open the same a moment before the lowered position of said beam has been reached, a brake 25 inserted between said arm and said shaft, said brake including a drum united with

said shaft, a brake band for said drum actuated by said arm, an electro-magnet, an armature on said brake band, and a shunt circuit for said electro-magnet connected 30 with said main circuit; whereby a train in said block will close the gap in the main circuit starting said motor through the intermediary of said gears and said shaft to lower said gate beam, said arm being simultaneously swung to open said switch and apply said brake while said electro-magnet attracts the armature to hold the gate beam in lowered position.

7. In a railway gate, the combination with 40 an insulated block of rails; of a gate beam adapted to stand normally in upright position, a circuit including a switch connected with a source of power, said rails providing a gap in said circuit, an element connected 45 with said beam for opening said switch when the beam is in lowered position, and a brake actuated by said element to retain the beam in said position.

In testimony whereof I affix my signature.

CHARLES W. HALL. [L.S.]
